UNITED STATES PATENT OFFICE

WILLETT M. RAYNOR, OF NEW YORK, N. Y.

TEMPORARY BINDER.

No. 892,084.

Specification of Letters Patent. Patented June 30, 1908.

Application filed December 13, 1907. Serial No. 406,381.

To all whom it may concern:

Be it known that I, WILLETT M. RAYNOR, a citizen of the United States of America, and resident of New York, in the county and State of New York, have invented certain new and useful Improvements in Temporary Binders, of which the following is a specification.

This invention relates to loose leaf binders and particularly to those having sectional binding posts for the purpose of increasing the capacity of the binder and permitting the addition of leaves to any practical extent.

The objects of this invention are: first, to provide a novel binder in which the unoccupied portion of the binding posts are confined within a housing, comprising one of the clips or binder members; second, the provision of means for locking the posts regardless of their position with relation to the housing or binder section so long as any portion of the posts project within the housing; and third, to provide binding members and sectional posts with sections of such length with relation to the binder members that the said binder members, when fastened to the posts, may always lie flush or in contact with the leaves. This invention might be termed a "flush leaf binder", in which the posts and binding means are invisible.

With the foregoing and other objects in view, the invention consists in the details of construction and in the arrangement and combination of parts to be hereinafter more fully set forth and claimed.

In describing the invention in detail, reference will be had to the accompanying drawings forming part of this specification wherein like characters denote corresponding parts in the several views, in which—

Figure 1, is a longitudinal sectional view of a binder embodying the invention; Fig. 2, is a detail view of one of the binder members, looking at the end thereof; Fig. 3, is a detail view showing the sectional posts and the relation of the housings thereto.

In the drawings A and B, denote the binding members, also termed "clips" which are approximately C-shaped in cross section, the contiguous or inner portions of the two members being parallel and adapted, when leaves are inserted, to bear on said leaves. The outer walls of the clips or casings are preferably struck up or bent to form internal channels *a* and *b*, respectively, thus producing

what may be termed "housings" designed for the purpose of receiving the locking mechanism and further for producing space for the accommodation of the binding posts C, which pass through the apertures *a'*, in the member A.

The binding posts are anchored in the member B, and extend through the apertures *b'*, of said member. The member A, is provided with stationary jaws D, at the apertures *a*, said jaws having recessed ends *d*, approximately conforming to the contour of the posts. The posts are forced against the jaws for the purpose of retaining the posts locked therein, by any suitable mechanism, operated from the exterior of the members, and I have found in practice that the locking members described in my application filed April 22, 1907, bearing Serial Number 369,551, is well adapted for use in this connection and said locking mechanism comprises the sliding dogs E, having slots *e*, to receive the guide pins F. The dogs are held normally away from the pins C, by springs G, which have the ends connected to the dogs and to the pin *g*, which pin *g*, is in the binding member. The dogs are projected into engagement with the posts C, against the action of the springs G, by the double cam H, on the face of the sliding plate I, which plate has a slot *i*, to receive the pin *g*. The inner ends of the dogs have beveled ends on the angle of the double cam H, as shown in dotted lines and as said plate I, is forced out by the key J, the cams project the dogs.

The extensions *e*, of the posts that is, the sections which are applied to the posts heretofore described are preferably of the same length as the posts attached to the member B, and the sections may be joined in any suitable manner but preferably by threaded shank and socket connections whereby the succeeding sections of the extension posts may be threaded into each other.

In carrying out the invention it is desirable that the extensions be practically uniform in length and that their length shall be no greater than the depth of the housing to which they are applied, for, if the length is greater than the depth of the housing, the parallel sections of said housings could not contact with the leaves applied to the posts, owing to the fact that the ends of the posts would contact the inner wall of a member before the lower portion thereof contacted

with the leaf. By enlarging the housing, that is increasing the depth of said housing, the sections of the posts may be of sufficient length to receive a given number of additional sheets before it becomes necessary to increase the length of the post by added sections and those portions of the posts not occupied by leaves are concealed within the housing.

10 Another advantage for the construction of the housing as shown and described, is that it permits a smooth finish when the leather or other cover is applied thereto.

I claim:

15 1. In a temporary binder, clamping members, binding posts carried by one of the members, and adapted to enter the opposite member, extensions for the posts, said extensions being equal in length to the depth of 20 the member of the binder which receives

them and means for locking the posts in the last mentioned member.

2. In a temporary binder, clamping members comprising housings having internal channels, posts secured to one member, the opposite member having apertures to receive the posts; said posts being equal in length to the depth of the channeled portion of the member, extensions for the said posts having the same relation to the housings as 30 the first mentioned posts, and means for locking the posts in the last mentioned member.

In testimony whereof I affix my signature in the presence of two witnesses this 13th day 35 of December, 1907.

WILLETT M. RAYNOR.
